[57] CLAIM

[21] Appl. No.: 856,828

The ornamental design for a carton blank, substantially as shown and described.

[22] Filed: Dec. 2, 1977

DESCRIPTION

[51] Int. Cl. ..... D9—03

FIG. 1 is a top plan view of a carton blank embodying our new design, the bottom plan view being substantially the same in appearance.

[52] U.S. Cl. D9/245

FIG. 2 is a side elevational view of the blank shown in FIG. 1.

[58] Field of Search ..... D9/245; 229/6 R, 11, 229/16 R, 17 R, 23 AB, 27, 28, 30, 36, 41 B, 41 C

The carton blank is constructed of material of conventional thickness, and the dashed lines in the drawing represent fold lines.
